WALL AND CEILING COVERING.

No.19,618.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,618, dated January 28, 1890.

Application filed December 26, 1889. Serial No. 335,049. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of a series of leaf-scrolls, which nearly fill the whole field of design 1, ornamented with fruit and flowers 2.

Right and left of central part of design is 15 an upright panel 7, divided in center with a band decorated with scrolls, the upper and lower parts of upright being filled in with

leaves which radiate from a semicircular button. There is an upper border of panels 3 and V-shaped scrolls 4, with band underneath 20 double scroll 5. At the base is a similar border, but reversed in position, 6.

What I claim is—

A design for a wall and ceiling covering herein shown and described, consisting of 25 central panel filled in with leaf-scrolls, fruit, and flowers, an upper and lower border, and uprights divided in center by band and ornamented with scrolls.

PAUL GROEBER.
